Primary Examiner — Christian P. McLean*Assistant Examiner* — Adam C Mager*(74) Attorney, Agent, or Firm* — Studebaker & Brackett PC(57) **CLAIM**

The ornamental design for a canopy for vehicle, as shown and described.

DESCRIPTION

FIG. 1 is a top perspective closed view, showing my new design for a canopy for vehicle,

FIG. 2 is a top closed view thereof,

FIG. 3 is a bottom closed view thereof,

FIG. 4 is a front closed view thereof,

FIG. 5 is a rear closed view thereof,

FIG. 6 is a right side closed view thereof,

FIG. 7 is a left side closed view thereof,

FIG. 8 is a top perspective open view thereof,

FIG. 9 is a top open view thereof,

FIG. 10 is a bottom open view thereof,

FIG. 11 is a front open view thereof,

FIG. 12 is a rear open view thereof,

FIG. 13 is a right side open view thereof; and,

FIG. 14 is a left side open view thereof.

The broken line showing is included for the purpose of illustrating portions of the canopy for vehicle that form no part of the claimed design.

1 Claim, 14 Drawing Sheets(56)
